UNITED STATES PATENT OFFICE.

DONALD DONALD, OF MASTERTON, NEW ZEALAND.

BALING-PRESS.

SPECIFICATION forming part of Letters Patent No. 787,501, dated April 18, 1905.

Application filed April 27, 1903. Renewed February 20, 1905. Serial No. 246,494.

To all whom it may concern:

Be it known that I, DONALD DONALD, a citizen of New Zealand, residing at Masterton, New Zealand, have invented certain new and useful Improvements in Baling-Presses, of which the following is a specification.

This invention relates to improvements in baling-presses, and more particularly in manually-operated presses which can be made in comparatively light and portable form and are especially adapted for use on farms and at stations where the heavy power-driven presses cannot be had.

The invention consists in the matters hereinafter set forth and more particularly pointed out in the appended claims when considered in connection with the accompanying drawings, in which—

Figure 1 is a side elevation of the press as it appears when loaded ready for the compressing operation to begin. Fig. 2 is a sectional side elevation thereof. Fig. 3 is an end elevation thereof. Fig. 4 is a side elevation of the press as it appears when the upper box is swung down upon the ground. Fig. 5 is a top plan view of the press as it appears when the upper box is swung down upon the ground and the door of the lower box is opened to admit the carriage, which is here shown as occupying a position part way within the lower box. Fig. 6 is an enlarged side elevation of the jack mechanism. Fig. 7 is a sectional detail thereof, taken on line 7-7 of Fig. 6. Fig. 8 is a perspective detail of the device for fastening the edges of the cloth within which the bale is formed. Fig. 9 is a sectional detail showing the manner in which the top plate is secured within the end of the upper box. Fig. 10 is a sectional side elevation of a carriage and bale as they appear when withdrawn from the lower box after the compressing operation is complete. Fig. 11 is a perspective view of a modified form of press embodying my construction in parts. Fig. 12 is a side elevation of the press as it appears while being used without the boxes.

The press thus illustrated consists of two boxes A and B, which are hinged together by pivotally-connected iron straps 1 and 2, so

that the top box can be swung down until it rests upon the ground opposite the lower box, as shown in Fig. 4. Said lower box is simply a four-sided inclosure open at both ends and bound around by stiffening-bands 3, preferably of angle-iron, which prevent its sides from bulging under pressure. The upper box A is of similar but somewhat lighter construction, which in its raised position fits closely upon the upper end of the box B and forms, in effect, a continuation or extension thereof.

One side 4 of the lower box A is made in the form of a door, which can be swung open to admit a carriage C, which consists of a rectangular base-plate 5 and vertical standards 6, secured to opposite sides of its base-plate and carrying jack devices D at their upper ends. The base-plate 5 is rectangular in shape and just large enough to fit within the lower box when closed, except that it has projections 7 at the middle of two of its opposite sides, which extend out through recesses or notches 8 in the corresponding sides of the box. These standards when the carriage is rolled into the box are accommodated by slots 9 in the sides of the box B and by openings 10, left between the wide ends of tapered filling-blocks 6, that are provided on these sides of the box within the angle-iron bands 3, which latter are here bent around them so as to form a sort of girder construction.

Cooperating with each of the jack devices D and forming a part thereof is a vertically-movable rack-bar 11, having upwardly-pointing teeth on its inner face, which are adapted to be engaged in alternation by loop-shaped links or pawls 12 and 13 of the jack, the ratchet-bar being drawn down through these loops as the jack is operated. This operation of the jack is accomplished in the usual manner by a lever 14, which can be swung up and down to give movement to an oscillating fulcrum 15. The links 12 and 13 are pivotally connected with this fulcrum on opposite sides of its center, as shown, and are thus caused to alternately slide up over and pull down upon the teeth of the rack-bar, against which they are held by springs 8. The pivotal point of the outer pawl 13 is preferably arranged farther from the center than that of 100

the inner pawl 12, so that during the downward movement of the lever, when the weight of the body can be thrown upon it, the leverage is reduced and the effective movement increased, as compared with that which occurs when the lever is lifted, as it must necessarily be, by main strength.

The ratchet-bars 11 are of such length that they may be raised to full height of the top box A when the latter is superposed upon the lower box and are adapted to be detachably connected with a cap or top plate 16, which fits within the box A and forms the opposing surface of the press to the base-plate 5. As herein shown, a transverse bar 17 of this cap projects out through the sides of the box and is temporarily secured to the upper ends of the ratchet-bars 11 by loops 18, and to accommodate this bar and permit the cap to be drawn down the full depth of the box A its sides are also provided with vertical slots 9 and its angle-irons with filling-blocks 7, separated by openings 10, like the corresponding parts of the lower box B.

In the operation of the press the top box A is swung over upon its hinges until it rests upon the ground opposite the lower box B, Figs. 4 and 5. The cap-plate 16 is then slid into the (now) lower end of the box A and allowed to rest upon cleats 19 on the inner sides of the box, which is cut out at one end of these cleats to admit of the insertion of the cap-plate in this manner, Fig. 11. The carriage C, having then been pushed into the lower box A, the open side or door 4 of the latter is closed and fastened by swing-links L or the like, and the box is then lined with a cloth or envelop E, within which the bale is to be inclosed, the cap-plate 16 being covered with a rectangular piece e of similar material for closing the head of the bale. Both boxes are then filled to the limit of their capacity with the material to be baled, and the top box A is swung back upon the box B, as shown in Figs. 1 and 2 of the drawings. The cap-plate now occupies the extreme top of the upper box, and all the material to be compressed is contained within the continuous receptacle formed by the two boxes between the base-plate 5 of the press and this cap-plate 16. The ratchet-bars 11 can now be lifted and connected to the cap-plate by their links 18, and thereupon the operation of the jack devices by moving their levers 14 like pump-handles will force all the material in the upper box down into the lower one. The compressing operation is now complete, and it only remains to sew the top piece E to the rest of the bale-cover and remove the bale from the press. To accomplish this, the top box is swung back upon the ground, the side or door 4 of the lower box is opened, and the press-carriage C withdrawn bodily, Fig. 10, together with the bale, which is still held tightly compressed between the base and top

plates of the carriage. This leaves the edges of the bale free for the sewing of the cover, after which the pressure is relieved by releasing the pawl-links of the jacks from the ratchet-bar, as may be done conveniently by means of hand-levers l, that are pivoted to each jack-housing at its upper end, Fig. 6. The bale may then be pushed out of the carriage and the latter moved back into the lower box ready for the operation to be repeated.

The raising and lowering of the top box A can be accomplished by main strength; but as a further improvement I have shown mechanism for aiding in the operation, consisting of a toothed rack-bar 20, which is pivoted to the upper box at 21 and intermeshes with a pinion 22 on the lower box. The shaft of this pinion is provided with a crank 23 and serves to pivotally support a triangular plate 24, in the corners of which antifriction-pins are mounted in position to engage and guide the back of the rack-bar and hold it in fixed relation to the pinion. Now by turning the crank 23 the rack-bar 20 can be positively projected and made to swing the box A up about its hinges to a point where the center of gravity of the box falls inside of the hinge, after which the crank movement may be reversed to ease the box down until it comes properly to rest upon the lower box A. Conversely when the upper box is emptied of its contents it may be swung back upon the ground again by turning the crank so as to tip it back off the lower box and then reversing the motion to lower it upon the ground. In either case the box may be assisted over the dead-center point by hand, if necessary, but ordinarily its momentum will suffice for the purpose.

As herein shown the handles H of the jack-levers 14 are made removable and are designed to be thrust through holes 26 in the upper edge of the top box A when open, Fig. 4, so as to prevent the material within the box from starting to fall out before it is completely swung over upon the lower box B, these handles being later withdrawn and used to operate the jacks. An antifriction-roller 27 is also herein shown as journaled in the upper end of each jack-housing to engage the back latch-bar 11 and resist the outward pressure of the latter due to the pull of the bars upon it, as shown in Fig. 6. This figure also shows the improved form of spring S provided for normally maintaining the links in engagement with the latch-bars, the same being made of heavy spring-wire bent to suitable form and clamped to the jack-housing by a nut 28 or the like.

The edges of the bag or cloth E require to be firmly held in order to prevent their being drawn down into the lower box B during the compressing operation, and to this end two of the opposite sides of the box are provided with rocking rods 29, which are held by cleats 30,

so that they can be oscillated through a considerable angle by their ends 31, the latter being bent outwardly to form handles for turning the rods, as shown in Fig. 8. These

5 rods are provided with a number of sharp points 32, onto which the cloth can be pressed and which when the rods are turned down will then prevent the edge of the cloth from being drawn into the box, the rods 29 being 10 locked in position to hold the points down by loops 33, which may be swung up over the handles 31.

To enable the carriage C of the press to be moved easily into and out of the box B, it is 15 herein shown as mounted upon rollers c, and as a further improvement these rollers are herein shown as grooved or otherwise formed to run upon tracks T, that are extended beneath the press on any foundation.

20 The press thus described is obviously simple and inexpensive in its construction and weighs so little as to be readily portable, while at the same time it is very powerful and can be made more so within any reasonable limit 25 by varying the proportions of its jack devices. It is convenient to handle and can be rapidly operated without undue exertion, and while more particularly designed as a wool-press is adapted to be equally well used for 30 baling cotton, hay, or any other material which can be packed into it.

In Fig. 11 I have shown a somewhat modified form of press embodying many of the 35 same features of the construction, but in which the separate carriage is dispensed with, the jack being bolted directly to the sides of the press, which thus take the place of the standards 6. This form of press is designed to be manufactured at still lower cost than the press 40 first described, and to this end is constructed almost entirely of wood, its boxes being bound around with bands formed of wooden beams joined together at their ends by diagonal bolts. The operation of this device is the same as 45 that of the press first described, except that the bale is removed directly from the lower box when the hinged side of the latter is swung back and except that in consequence the bale must be sewed up within its envelop 50 before being removed from the box.

The improved mechanism heretofore described for swinging the upper box upon its hinges may be equally well applied to the 55 modified construction last referred to, if so desired, and this mechanism may also be found desirable in various connections where a simple and effective power device for raising and lowering a load under similar circumstances is required.

60 Fig. 12 shows how the press could be utilized and operated in a horizontal or upright position independently of either of the boxes by placing the material to be pressed between the pressure-plates and operating the levers 65 as hereinbefore described. The material so

compressed may then be secured in that form by having bands or other wires around the bale and fastening the ends.

I claim as my invention—

1. A press consisting of a lower box, a top 70 box hinged to the lower box but adapted to be swung down beside it, a pressure-plate in the lower box, a movable pressure-plate in the upper box, means for detachably connecting said plates, and jack devices for drawing the connected plates together, substantially as described.

2. A press consisting of a lower box, a top 80 box hinged to the lower box but adapted to be swung down beside it, a pressure-plate in the lower box, a movable pressure-plate in the upper box, means for detachably connecting said plates, jack devices for drawing the connected plates together, and mechanism for raising the top box upon the lower box, substantially as described.

3. A press consisting of a lower box, a top 90 box hinged to the lower box but adapted to be swung down beside it, a pressure-plate in the lower box, movable pressure-plate in the upper box, means for detachably connecting said plates, jack devices for drawing the connected plates together, and mechanism for raising the top box upon the lower box and for lowering the top box to the ground, substantially as described.

4. A press consisting of a lower box, a top 100 box hinged to the lower box but adapted to be swung down beside it, a pressure-plate in the lower box, a movable pressure-plate in the upper box, means for detachably connecting said plates, jack devices for drawing the connected plates together, and mechanism for swinging the top box upon its hinges comprising a rack-bar pivoted to one of the boxes, 105 and a rotatable pinion journaled on the other box and held in engagement with the rack-bar to project or retract the same, substantially as described.

5. A press consisting of a lower box, a top 110 box hinged to the lower box but adapted to be swung down beside it, a pressure-plate in the lower box, movable pressure-plate in the upper box, means for detachably connecting said plates, jack devices for drawing the connected 115 plates together, mechanism for swinging the top box on its hinges comprising a rack-bar pivoted to the top box, a pinion journaled on the lower box and intermeshing with the rack-bar, and a crank for rotating said pinion, substantially as described.

6. A press consisting of a lower box, a top 120 box hinged to the lower box but adapted to be swung down beside it, a pressure-plate in the upper box, means for detachably connecting said plates, a mechanism for swinging the top box on its hinges comprising a rack-bar pivoted to the upper box, a pinion journaled on the lower box, a crank rotating said pinion, and a swing- 125 130

ing plate pivoted about the pinion-shaft and having parts embracing the rack-bar to hold it in mesh with the pinion, substantially as described.

5. 7. A press consisting of a lower box, a top box hinged to the lower box but adapted to be swung down beside it, a pressure-plate in the lower box, a movable pressure-plate in the upper box, means for detachably connecting said plates, a mechanism for swinging the top box on its hinges comprising a rack-bar pivoted to the upper box, a pinion journaled on the lower box, a crank rotating said pinion, and a swinging plate pivoted about the pinion-shaft and carrying rollers engaging the back of the rack-bar to hold it in mesh with the pinion, substantially as described.

8. A press consisting of a lower box, a top box hinged to the lower box, a pressure-plate in the lower box, a movable pressure-plate in the upper box, means for detachably connecting said plates, and jack devices for drawing the connected plates together, each comprising a ratchet-bar and a pair of pawls pivoted to an oscillatory fulcrum and engaging the ratchet-bar, one of said pawls being connected with the fulcrum at a greater distance from its axis of oscillation than the other, substantially as described.

30. 9. A press consisting of a lower box, a top box hinged to the lower box, a pressure-plate in the lower box, a movable pressure-plate in the upper box, means for detachably connecting said plates, jack devices for drawing the connected plates together, each comprising a ratchet-bar and a pair of pawls pivoted to an oscillatory fulcrum and engaging the ratchet-bar, the outer one of said pawls being connected with the fulcrum at a greater distance from its axis of oscillation than the other, substantially as described.

10. A press consisting of a lower box, a top box, hinged to the lower box but adapted to be swung down beside it, a pressure-plate in the lower box, a movable pressure-plate in the upper box, means for detachably connecting said plates, jack devices for drawing the connected plates together, said jack devices each comprising a ratchet-bar and a pair of pawls pivoted to an oscillatory fulcrum and engaging the ratchet-bar, and a lever pivoted to the housing of the jack above the fulcrum and adapted to engage the pawls to force them away from the rack-bar, substantially as described.

55. 11. A press consisting of two open-ended separable boxes, opposing pressure-plates in the respective boxes, and lever jack devices applied between the two plates to draw one toward and into the opposite box, substantially as described.

12. A press consisting of two open-ended separable boxes, two opposing pressure-plates, in the respective boxes, and jack devices for drawing one of the plates toward and

into the opposite box, comprising ratchet-bars secured to one plate and lever, and pawl devices secured to the other plate and operatively engaging the ratchet-bars, substantially as described.

13. A press consisting of opposing pressure-plates and jack devices for drawing the connected plates together, each comprising a ratchet-bar and a pair of pawls pivoted to an oscillatory fulcrum and engaging the ratchet-bar, one of said pawls being connected with the fulcrum at a greater distance from its axis of oscillation than the other, substantially as described.

14. A press consisting of two open-ended separable boxes, two opposing pressure-plates, in the respective boxes and jack devices applied between the two plates to draw one toward and into the opposite box, each comprising a ratchet-bar, and a pair of pawls pivoted to an oscillatory fulcrum and engaging the teeth of the ratchet-bar, substantially as described.

15. A press consisting of a box, one side of which can be opened, and a press-carriage adapted to be moved into the box through its open side and comprising upper and lower pressure-plates, and jack devices for drawing the plates together within the box, substantially as described.

16. A press consisting of a box, one side of which can be opened, and a press-carriage adapted to be moved into the box through its open side and comprising upper and lower pressure-plates, and jack devices for drawing the plates together within the box, the sides of the box being provided with slots through which the jack devices project to bring their operating-levers outside of the box, substantially as described.

17. A press consisting of a lower box, one side of which can be opened, a top box hinged to the lower box, a press-carriage adapted to be moved into the lower box through its open side, and comprising a lower pressure-plate, and jack devices secured to said plate, a movable pressure-plate in the upper box, and means for detachably connecting the movable plate and jack devices, substantially as described.

18. A press consisting of a lower box, one side of which can be opened, a top box hinged to the lower box, a press-carriage adapted to be moved into the lower box through its open side, and comprising a lower pressure-plate, and jack devices secured to said plate, a movable pressure-plate in the upper box, the sides of the box being provided with slots through which the jack devices project to bring their operating-levers outside of the box, and means for detachably connecting the movable head and jack devices, substantially as described.

19. A press, consisting of two open-ended separable boxes placed open end to open end, a stationary pressure-plate closing one end of

one of the boxes, a movable pressure-plate closing the opposite end of the other box, this movable pressure-plate being adapted to pass into the open end of the opposite box, and

5 means for forcing the movable plate toward and into the other box to thereby compress the material therein and leave the first-named box empty and free to be removed.

20. A press consisting of two open-ended 10 boxes placed open end to open end, one of the boxes being removable from the other and capable of being inverted, a pressure-plate in each of the boxes, and means for forcing one of the pressure-plates toward and into the open 15 end of the box containing the other pressure-plate, for the purposes set forth.

21. A press, consisting of two separable 20 boxes placed one upon the other, the upper box being capable of being removed and inverted, removable means for holding the material in the upper box while the same is being placed upon the lower box, pressure-plates in the respective boxes, and means for forcing one of the pressure-plates toward and into the 25 opposite box, for the purposes set forth.

22. A press, consisting of a lower box having its lower end closed by a pressure-plate, and its upper end open, an upper box mounted on the lower box and capable of being 30 moved and inverted, a movable pressure-plate

closing the upper end of the upper box, and means for drawing down the upper pressure-plate toward and into the lower box, for the purposes set forth.

23. A press, consisting of a box, one side 35 of which can be opened, and a press-carriage adapted to be moved into the box through its open side, and comprising upper and lower pressure-plates, and jack devices for drawing the plates together within the box, said jack 40 devices being connected to said pressure-plates and being removable from the press-box therewith.

24. A press, consisting of a lower box, one side of which can be opened, a pressure-plate 45 in this lower box, an upper box containing a pressure-plate, and means for drawing down the upper pressure-plate into the lower box, said means and said pressure-plates constituting a bale-clamping device which is capable of 50 being removed through the open sides of the lower box.

In testimony that I claim the foregoing as my invention I affix my signature, in presence of two subscribing witnesses, this 24th day of April, A. D. 1903.

DONALD DONALD.
